UNITED STATES PATENT OFFICE.

FRANK COLLINS, OF NEW YORK, N. Y., ASSIGNOR TO MUTUAL SUNSET-LAMP MFG. CO. INC., OF NEW YORK, N. Y., A CORPORATION OF NEW YORK.

DESIGN FOR A LAMP-PEDESTAL ARM.

Application filed February 2, 1929. Serial No. 29,891. Term of patent 3½ years.

To all whom it may concern:

Be it known that I, FRANK COLLINS, a citizen of the United States, residing in New York, in the county of New York and State of New York, have invented a new, original, and ornamental Design for a Lamp-Pedestal Arm, of which the following is a specification, reference being had to the accompanying drawing, forming part thereof.

Figure 1 is a side elevation of a lamp pedestal arm, the dotted lines indicating a use of the arm, showing my new design, and

Figure 2 is an end elevation thereof.

I claim:

The ornamental design for a lamp pedestal arm, as shown and described.

FRANK COLLINS.
